UNITED STATES PATENT OFFICE.

RICHARD RAINES, OF NEW YORK, N. Y.

HIGH-TENSION-CURRENT SYSTEM.

1,103,835.

Specification of Letters Patent. Patented July 14, 1914.

Application filed March 9, 1912. Serial No. 682,723.

To all whom it may concern:

Be it known that I, RICHARD RAINES, a citizen of the United States of America, residing at New York, in the county of New York and State of New York, have invented new and useful Improvements in High-Tension-Current Systems, of which the following is a specification.

This invention relates to improvements in high tension current systems and has particular application to systems of this type for igniting the gases of explosive engines, although it is to be understood that the useful application of my invention is not confined to this particular purpose, as the same may be advantageously used wherever it is desired to employ high tension electric currents.

In carrying out the present invention, in the present instance, it is my purpose to provide a system of generating and transmitting high tension electric currents, that is currents of a relatively high voltage, by means of which the gases of explosive engines, such as hydrocarbon gas mixed with air, used in gas and naphtha engines, may be exploded to cause the expansion of such gases to drive the piston of the engine, such system involving primary and secondary circuits and a circuit interrupting device in the primary circuit and adapted to break the primary circuit at predetermined intervals, such device being adjustable to vary the interval of breaking of the primary circuit so as to retard or advance the spark in the engine, according to the cycle of operation of such engine. Furthermore, I aim to provide a system of the type set forth which shall include a magneto or dynamo electric machine and a transformer having its primary circuit in series with the armature of such machine and its secondary circuit terminating in sparking points arranged within the engine cylinders, a circuit interrupting device being interposed in the primary circuit and driven from the armature of the magneto to effect the make in the primary circuit at certain periods relative to the position of the engine piston, such interrupting device embodying means operable to close the circuit at predetermined intervals and adjustable to close such circuit sooner or later relative to the cycle of operation of the engine whereby to advance or retard the spark.

It is also my purpose to provide a system of this character wherein the circuit in the magneto may be made at certain intervals, for instance in a bipolar machine, once in each rotation of the armature, the time at which the circuit is made being relative to the position of the armature within the field and the duration of the completion of such circuit being variable according to the current pulsations required to produce the desired length, intensity, and duration of spark. As to the time at which the circuit is made, the desired results can only be produced by effecting each make of the circuit at a point in the rotation of the armature when it has passed its medial position between the poles of the field and has entered into the following one from which it is receding, the exact point being variable and determined according to the particular spark effect which it is desired to produce. The farther the armature has receded from its medial position when the make is effected, the greater the intensity of the spark which can be produced. The duration of each make of the circuit may be varied in different machines to correspond to the time required for rotating the armature to travel through for about one degree to twenty degrees of its path of rotation, according to the efficiency of the interrupter employed and the nature of the pulsation required to give the desired spark effect.

With the above and other objects in view, the invention consists in the construction, combination and arrangement of parts hereinafter set forth in and falling within the scope of the appended claim.

In the accompanying drawings I have disclosed one preferred and practical embodiment of my invention and in these drawings; Figure 1 is a view in side elevation of a magneto electrical machine constructed in accordance with the present invention. Fig. 2 is a vertical longitudinal sectional view of the same. Fig. 3 is a sectional view through one end of the magneto showing the circuit interrupting device in elevation. Fig. 4 is a sectional view of a part of the interrupting device.

Similar reference characters designate like parts throughout the several views.

Referring now to the accompanying drawings in detail, my improved high tension electric current system includes a mag-

105

110

neto M embodying a base 1 of suitable conducting material upon which is mounted the field of the machine composed in this instance of a plurality of horse shoe magnets, 5 three being shown as an example, 2, 3 and 4, each magnet preferably embodying a laminated structure, such as the laminations 5 and 6, shown in Fig. 3. The opposite ends of each magnet and the proximate ends of 10 adjacent magnets are suitably fastened to oppositely disposed field pieces 7 and 8, which are preferably made of laminations of soft iron or the like, and have their inner opposing surfaces concaved as at 9, 9 to accommodate the position and rotation of the 15 armature of the machine.

Projecting upwardly from the base 1 and secured thereto in any suitable manner are spaced parallel standards 10 and 11 embracing the field magnets at the opposite sides of the field, the standard 10 being provided with an enlarged opening 12 while the standard 11 is formed with a small opening 13 and in this last named opening is mounted 20 a bearing 14 of good conducting material, while in the enlarged opening 12 of the standard 10 is a bearing 15 constructed of insulating material and carried by the opposite ends of set screws 16 threaded 25 through openings in the walls of the opening 12 in the standard 10 at diametrically opposite points. These bearings 14 and 15 receive the armature shaft 17, which shaft extends beyond its respective bearing members 30 and carries the armature designated as an entirety by the letter A and supports the same for rotation within the field of the machine and between the pole pieces 7 and 8. Each of the pole pieces 7 and 8 is provided 35 with spaced parallel tie rods 18 extending beyond the ends of such pieces and designed to enter slots 19 in the standards 10 and 11 so as to hold the parts in assembled position, nuts 20 being threaded 40 onto the projecting extremities of the rods 45 18 for fastening purposes.

The armature preferably consists of a rectangular frame composed of the side bars 21 and the end bars 22 bolted or otherwise 50 secured together in frame formation and insulated one from the other as at 23. Threadedly engaging the side bars 21, 21 and extending between the same and preferably centrally of the end bars 22, 22 is a 55 tube 24 carrying a core 25 formed of a bundle of soft iron wires, and encircling the tube 24 and in inductive relation to the core 25 is a bobbin 26 carrying a coil of wire adapted to receive currents from the 60 core 25 in the rotation of the armature within the field, as will be readily understood. From this construction, it will be seen that in the rotation of the armature within the field, a positive rise and fall of 65 the current within the armature is effected

owing to the position of the core 25 with respect to the field pieces 7 and 8, thereby inducing in the armature a pulsating current which is at its maximum strength or capacity when the armature core is in a horizontal position or directly across the field, the rise and fall of such currents occurring when the armature enters and leaves the field, the current being at its minimum strength when the core 25 is at right angles to the field or in a vertical position, it being understood of course that the terms horizontal and vertical positions are used in this instance for the sake of clearness and assuming that the machine is in an upright position as shown in Fig. 1.

Fixed to the base 1 and in electrical contact therewith and projecting upwardly therefrom in proximity to the opening 12 in the standard 10, is a support 27 provided with an opening in which is arranged an insulated bushing 28 designed to receive the free extremity of the shaft 17 beyond the bearing 15, and arranged within the opening 12 of the standard 10, is an annulus 29 coaxial with the bushing 28 and formed with an outstanding flange or collar 30 designed to support the circuit interrupting device. This circuit interrupting device includes an annular housing or casing 31 rotatably mounted upon the collar 30 of the annulus and provided with an outstanding annular flange 32 designed to frictionally engage the inner surface of the support 27, such support assisting the flange 30 in supporting the casing. Fixed to the casing 31 at an appropriate point thereon and insulated therefrom, is a binding post 33 extending within the casing and carrying at its inner end a yieldable contact strip 34. Fixed to the inner side of the casing 31 in proximity to the contact strip 34 is an ear 35 in which is pivotally mounted an arm 36 carrying at its free end a laminated contact roller 37 adapted to engage the contact strip 34 at predetermined intervals in the rotation of the armature so as to effect the making or closing of the armature circuit. In order to actuate the roller 37 to make the circuit at certain intervals in the rotation of the armature and to bring about such closing of the circuit from the armature shaft, I utilize a cam 38 composed preferably of a laminated structure and mounted upon the side of the armature shaft 17 within the casing 31 and insulated from such shaft as at 39. To rotate the shaft 17 and the cam 38 as a unit, the latter is keyed to such shaft by means of spring clips 40 mounted in pairs upon the opposite faces of the cam 41 and at diametrically opposite points and adapted to be engaged in grooves 41 in the shaft 17, such spring clips being held in the grooves by means of bolts and nuts 42 passed through alining apertures in the 130

strips and the cam, the release of such bolts and nuts permitting the spring clips to disengage themselves from the grooves whereby the cam may be removed from the shaft.

5 Fixed to the end of the shaft 17 within the bushing 28, is a binding post 43, which with the binding post 33, form the terminals of the armature circuit when such circuit is closed.

10 In accordance with the present invention, I make use of a transformer T which may be of any suitable or preferred construction and design and embodies primary and secondary windings or circuits, the terminals of the 15 primary winding being indicated at 44, 45, while the terminals of the secondary circuit or winding are indicated at 46, 47. Leading from the terminal 44 of the primary circuit of the transformer is a conductor 48 terminally connected to the binding post 43 of the 20 armature shaft 17, and leading from the terminal 45 of such transformer circuit is a conductor 49 terminally connected to the binding post 33 on the casing 31, thus arranging the armature in series with the 25 primary circuit of the transformer. This circuit may be traced as follows: from binding post 44 by way of conductor 48 to the side of the armature shaft 17 within the casing 31, thence through the respective end bar 22 of 30 the armature frame to the bobbin 26 of the armature through the medium of a conductor 50, whence the current is conveyed to the opposite end bar 22 of the armature frame 35 by way of a conductor 51, and from this end bar of the frame the current is taken to the lower part of the standard 11 through the opposite side of the armature shaft 17, thence through the base 1, support 27, casing 31, 40 ear and arm 35 and 36 respectively, and roller 37 so that when said roller is actuated to engage the contact strip 34, the primary circuit of the transformer and the circuit through the armature are completed, thereby 45 energizing the primary circuit of the transformer and inducing current in the secondary circuit of such transformer.

The casing 31 is adjustable about the cam 38 so as to vary the interval of closing the 50 primary circuit, and for this purpose a lever 52 is connected to the outer surface of the casing 31 at an appropriate point. As the roller 37 and the binding post 33 are carried by the casing, it follows that in the movement of the casing, such roller and binding post will be moved therewith, so that such roller may be adjusted relatively to the cam to cause the latter to actuate the roller to close the circuit to vary the time of such 55 closing of the circuit according to the position of the armature within the field, and for another purpose which will presently appear. Thus, the roller 37 may be moved about the cam to be actuated to circuit closing position by such cam when the core 25 of

the armature is disposed directly across the field, thereby enabling a current of relatively great strength to be supplied to the primary circuit in the transformer. In other words, the strength of the current from the magneto or dynamo electric machine may be varied according to the circumstances or requirements in any particular case.

70 In the present embodiment of my invention, I have shown the same as being utilized to explode the gases of an explosive engine. Such engine, is designated at E and in this instance is of the four cylinder type, each cylinder being provided with a sparking device, such as a spark plug, one terminal of which spark plug is grounded upon the engine frame and the other terminal connected in circuit with the secondary circuit of the transformer. As the engine is of the four cylinder type, it is necessary to employ a distributor so that the circuit to a particular cylinder may be closed at the proper time, usually when the piston of such cylinder is on the other side of its dead center subsequent to compressing the gas to its 85 maximum.

Secured to the standard 11 and insulated therefrom is a housing 53 provided with a bearing 54 coaxial with the bearing 14 of the standard 11 and receiving this end of the armature shaft 17, such end of the armature shaft being connected up to the engine or other suitable driving mechanism by a belt wheel 55 or the like. Arranged within the housing 53 and in the present instance at 90 right angles to the armature shaft, is a distributor shaft 56 mounted at one extremity within an insulated bearing 57 and carrying at its opposite or free extremity a disk 58 constructed of insulating material. The 95 shaft 56 adjacent to the disk 58 is revolvably mounted within a bracket 59 which bracket is secured to and insulated from the standard 11, but in electrical communication with the shaft 56. A plurality of binding posts 100 60 are carried by the housing 59 in proximity to the disk 58, four of such binding posts being herein shown incident to the number of cylinders of which the engine is composed, and secured to the free ends of each 105 binding post 60 within the housing 53 is a spring contact strip 61, such strips being successively engaged by a contact 62 carried by the disk 58 and electrically connected to the shaft 56 and operable to engage the strips 61 in the movement of the distributor shaft. This distributor shaft 56 is preferably driven from the armature shaft 17 and in the present instance is provided with a worm wheel 63 keyed upon said shaft and insulated therefrom and meshing with a worm 64 upon the side of the armature shaft 17 within the housing 53 so that in the movement of the armature shaft rotary motion may be transmitted to the distributor shaft to rotate 110 115 120 125 130

the disk 58 and engage the contact 62 carried by such disk with the contact strips 61 on the binding posts 60, successively.

Leading from the binding post 47 of the 5 secondary circuit of the transformer is a conductor 65 terminally connected to the bracket 59, and leading from the binding post 46 of such transformer circuit is a conductor 66 grounded upon the frame of the 10 engine E, while to each binding post 60 of the distributor is connected a conductor 67 terminally connected to one of the sparking devices of a cylinder of the engine, so that in the movement of the distributor, the secondary circuit may be completed to energize 15 the sparking devices of the cylinders successively and at the proper time. As the conductor 65 of the secondary circuit of the transformer is in electrical communication 20 with the bracket 59 and consequently distributor shaft 56 and the conductor 66 of such circuit of the transformer grounded upon the engine frame, the secondary transformer circuit may be traced as follows, 25 binding post 47, conductor 65, bracket and distributor shaft 59 and 56 respectively, contact 62, one of the strips 61 and its coöperating conductor 67, engine frame, conductor 66, and binding post 46, it of course being 30 understood that the current is supplied to the respective engine cylinders one after the other and at the proper time according to the cycle of operation of the engine.

To retard or advance the spark within 35 the engine cylinders, the casing 31 of the circuit interrupting device is adjusted around the cam 38 so that the roller of such circuit closing device may be acted upon sooner or later by the cam relative to the 40 position of the piston within the engine cylinder, consequently causing the spark to be advanced or retarded according to the adjustment of the circuit closer.

In event that the engine should be composed of only one cylinder, the distributor 45 may be eliminated, or should the engine be composed of two cylinders, a switch or distributor may be utilized embodying but two binding posts. In other words, the number 50 of binding posts required for the distributor is dependent upon the number of cylinders employed in the engine, as will be readily understood by those skilled in the art.

In order to give an initial spark so that 55 the explosive engine may pick up its cycle of operation and actuate the magneto, should such engine and magneto be connected, I make use of an auxiliary circuit which in this instance includes a battery 68 connected 60 at one side to a binding post 69 by way of a conductor 70 and having its opposite side

connected by a wire 71 to the conductor 48 of the primary circuit of the transformer, a binding post 72 being connected by way of a wire 73 with the conductor 49 of the transformer primary circuit. Mounted upon the casing of the transformer T is a two-way switch 74 adapted to engage a contact 75 to close the battery circuit between the terminals or binding posts 69 and 72 and a contact 76 to close the magneto circuit, the battery circuit being completed when the switch is on the contact 75 through conductor 70, binding post 69, switch, binding post 72, conductor 73, the primary circuit of the transformer, thence back to battery by way of binding post 44, a portion of conductor 48 and wire 71.

In the event of my system being applied to an automobile, a system of levers and connecting rods may be employed and connected to the lever 52 of the circuit interrupting device so that such device may be operated from the driver's seat on the vehicle to advance and retard the spark.

From the foregoing description taken in connection with the accompanying drawing, the construction, mode of operation, and method of employing my invention will be readily understood by those skilled in the art to which the invention appertains; and while I have herein shown and described one preferred embodiment of my invention by way of illustration, it is to be understood that I do not limit myself to the exact details of construction herein described and delineated, as modification and variation may be made within the scope of the claim and without departing from the spirit of my invention.

I claim:

A circuit interrupting device comprising a cylindrical casing capable of rotary movement, contacts on the inner surface of said casing and normally spaced apart, a cam within said casing and composed of a laminated structure and adapted to actuate said contacts to circuit closing position, a shaft carrying said cam, and a rigid connection between said cam and shaft, said connection comprising spring fingers fastened to the opposite faces of said cam at diametrically opposite points and engageable in grooves formed in the adjacent part of the shaft of said armature.

In testimony whereof I affix my signature in presence of two witnesses.

RICHARD RAINES.
